UNITED STATES PATENT OFFICE

2,484,661

FRAMED DESIGN FOR HANDBAGS,
LUGGAGE, AND THE LIKE

John G. Vogel, New York, N. Y.

Application November 27, 1944, Serial No. 565,307

3 Claims. (Cl. 40—152)

1

This invention relates to new and useful improvements in a framed design arrangement for handbags, luggage and the like.

More particularly, the invention proposes an improved framed design arrangement characterized by a backing sheet with a framing strip mounted thereon forming a frame for an illustration or monogram, and a plate for said illustration or monogram mounted behind said framing strip and held in position by the framing strip.

The invention contemplates using the new framed design arrangement directly on the side of handbags, other types of bags, luggage and the like, or using the same on a flap which is attached to the handbag or other type of bag, luggage and the like.

Still further the invention proposes the construction of a framed design arrangement as described, which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a side elevational view of a handbag provided with a framed design arrangement constructed in accordance with this invention.

Fig. 2 is a sectional view of the flap and framed design arrangement shown in Fig. 1, this view being taken on the line 2—2 of Fig. 1.

Fig. 3 is a side elevational view of a handbag provided with a framed design arrangement constructed in accordance with still another form of this invention.

Fig. 4 is a fragmentary enlarged sectional view taken on the line 4—4 of Fig. 3.

Fig. 5 is a perspective view of the plate with the illustration shown in Figs. 3 and 4.

Fig. 6 is a fragmentary detailed view of the framing strip used in Figs. 3 and 4.

Fig. 7 is a side elevational view of a purse provided with a framed design arrangement constructed in accordance with another form of this invention.

Fig. 8 is a fragmentary vertical sectional view taken on the line 8—8 of Fig. 7.

Fig. 9 is a similar view to Fig. 8, but showing a modified form of the invention.

The framed design arrangement, in accordance with that form of the invention disclosed in

2

Figs. 1 and 2, includes a backing sheet 10 such as a flap which is attached at its top edge to the frame 11 of a handbag 12 or other object. A framing strip 14 is mounted on the backing sheet 10, preferably with a line of stitches 15 along its edges. This framing strip 14 forms a circular frame for an illustration or monogram plate, such as the plate 16 and also forms a frame for a transparent sheet 16' which covers the plate 16. This plate 16 has the illustration or monogram printed or painted or in any other manner formed on its front face.

The circular framing strip 14 comprises a strip of bendable material which has its inner edge portion 17 bent inwards. This inner edge portion 17 is pasted down to the inner face of the strip 14. The plate 16 may be securely mounted within the framing strip by adhesive between the contacting faces of the plate 16 and the inwardly bent edge portion 17.

In Figs. 3—6 a modified form of the invention is disclosed which distinguishes from the prior form in the fact that a sectional framing strip 20 is attached upon a backing strip 21, which in this case comprises a side wall of a handbag 22. The framing strip 20 is rectangular and formed of four separate sections which have their ends abutting one another and which are individually secured to the backing strip 21, as will become clear as this specification proceeds. Each of the sections of the framing strip 20 has an inner edge portion 23 bent inwards and pasted down on the inner face thereof. A rectangular sectional auxiliary framing strip 25 is used beneath the framing strip 20. This auxiliary strip 25 preferably is a celluloid strip. At spaced points the auxiliary strip 25 is provided with downwardly stamped tongues 26 stamped from the material thereof. These tongues 26 of the strip 25 normally engage corresponding openings 27 formed along the edge of the plate 28 which is provided with an illustration, monogram or the like 29. A line of stitches 30 extends along the edge portions of the framing strip 20 and the auxiliary framing strip 25 and extends through the material of the backing sheet 21 by which the frame strips are mounted in position.

An important feature of this form of the invention resides in the fact that the plate 28 is removably held in position by the flexible tongues 26. When desired the inner edge portion of the framing strip 20 and the auxiliary framing strip 25 may be flexed upwards so that the tongues 26 are freed from the openings 27 and then the plate 28 may be removed and replaced.

In Figs. 7 and 8 still another form of this invention is illustrated in which it is applied to a purse 30'. This purse 30' has a backing sheet 31 which in this case is the outer material of the purse. This backing sheet 31 is formed with an opening 32 forming the mouth of a pocket 33 which is mounted to the back of the sheet 31 and around an opening 34 which acts as a framing opening for a plate 35. The plate 35 is provided with an illustration or monogram. The pocket 33 has an inwardly bent edge portion 36 which engages the edge portions of the plate 35 and acts as a framing strip for holding the plate 35 in position. A slide fastener 37 is used for closing the mouth opening 32.

When the slide fastener 37 is opened it is possible to reach into the pocket 33 and remove the plate 35 from the framing strip 36. The plate 35 may then be replaced or exchanged with a similar plate.

In Fig. 9, the painted picture plate 16* is shown to be mounted on an interlining 40 by adhesive or by any other means. The purse 41 forms an opening 42 and a finished edge 43 by folding inwardly the edges 44 of the purse material 41, around the opening 42.

A suitable lining material 45 is also provided within the purse.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A frame design arrangement for handbags and the like, comprising a rectangular framing strip and a backing sheet therefor forming an enclosing frame, a plate having a design mounted between said backing sheet and said framing strip, said framing strip being flexible, an auxiliary rectangular framing strip of flexible material disposed between said first-named framing strip and said backing sheet to overlap the edge portions of said plate and formed with stamped-out tongues, said plate having openings formed in the edge portions thereof into which said tongues extend, whereby said framing strip and said auxiliary framing strip may be flexed away from said plate to disengage said tongues from said openings freeing said plate to be removed.

2. A frame design for handbags, comprising a rectangular framing strip of flexible material and a backing sheet therefor forming a frame, a plate having an illustration thereon and

disposed on said backing sheet under said framing strip, an auxiliary rectangular framing strip of flexible material disposed between said first-named framing strip and said backing sheet to overlap the edge portions of said plate and having inwardly extending resilient stamped-out tongues, said plate having marginal edge openings into which said tongues extend, whereby said framing strip and said auxiliary framing strip may be flexed away from said plate to disengage said tongues from said openings freeing said plate to be removed, the material of said auxiliary framing strip from which said tongues are stamped being covered by said first-mentioned framing strip.

3. A frame design arrangement for handbags and the like, comprising a rectangular framing strip of flexible material and a backing sheet therefor, a plate carrying an illustration disposed on said backing sheet under said framing strip, a second rectangular framing strip of flexible material disposed between said first-named framing strip and said backing sheet to overlap the edge portions of said plate and formed with inwardly extending resilient tongues stamped from the material thereof, said plate being formed with marginal openings into which said tongues extend, said framing strips and said backing sheet having their outer peripheral edges of said plate and secured together by lines of stitches, whereby the inner edges of said framing strips are free to be flexed away from said plate withdrawing said tongues from said openings and freeing said plate to be removed.

JOHN G. VOGEL.
